UNITED STATES PATENT OFFICE

MICHAEL AUGUST ROGGE MAN, OF REVERE, MINNESOTA

TRACTOR ATTACHMENT

Application filed January 25, 1930. Serial No. 423,464.

The present invention relates to an attachment for tractors of that type wherein the front dirigible wheels are relatively close together and the object of the attachment resides in the provision of a supplemental bolster structure affording a front axle so that the front dirigible wheels may be disposed farther apart to cause the tractor to ride more steadily to cause the same to not so easily topple over.

Another very important object of the invention resides in the provision of an attachment of this nature which is simple in its construction, inexpensive to manufacture, easily put in place, strong and durable, and thoroughly efficient and reliable in use and operation.

With the above and numerous other objects in view as will appear as the description proceeds, the invention resides in certain novel features of construction, and in the combination and arrangement of parts as will be hereinafter more fully described and claimed.

25 In the drawing:

Figure 1 is a front elevation of a tractor showing my improved attachment thereon,

Figure 2 is a side elevation thereof showing portions in section,

30 Figure 3 is a perspective view of the bolster assembly,

Figure 4 is a sectional view taken substantially on the line 4—4 of Figure 2,

Figure 5 is a sectional view taken on the 35 line 5—5 of Figure 2,

Figure 6 is a sectional view taken on the line 6—6 of Figure 5, and

40 Figure 7 is a perspective view of an arm for attachment to the steering mechanism of the tractor.

Referring to the drawing in detail it will be seen that the letter F denotes a conventional frame of a well known type of tractor.

The bolster constituting this invention 45 comprises a pair of cross bars 5 and 6 which are bolted to the front end of the frame by means of U-bolts 7. A vertical plate 8 is secured to the central portions of the cross bars 5 and 6 depending below the lower 50 cross bar 6 and having a side flange 9.

A vertical bolster bar 10 is fixed to the plate 8 by rivets or the like against the flange 9 thus preventing any shearing of the rivets or the like and this bar 10 extends below the lower end of the plate 8. The lower end of 55 the plate 8 and the adjacent portion of the bar 10 are bolted by means of a U-bolt 11 to the conventional bolster structure S.

An axle 12 is bolted at its center to the lower end of the bolster bar 10 as is indicated at 14. The steering knuckles 15 are mounted on the ends of the axle 12 and wheels 16 are journaled on the steering knuckle. These wheels 16 of course, are the same wheels which were taken off the axle of the bolster structure S. Arms 17 of the steering knuckles 15 having a connecting rod 18 therebetween with the center of which is pivotally engaged the rear end of an arm 19 which is secured to the conventional steering 70 mechanism of the tractor.

A V-shaped brace 20 has its ends secured to the end portions of the axle 12 to extend horizontally and rearwardly. A V-shaped brace 21 has its ends secured to the sides of 75 the frame F and inclines downwardly and forwardly. The apexes of the braces 20 and 21 are bolted and pivoted together as at 22. Braces 23 extend from the lower portions of the braces 21 to incline upwardly and forwardly and are attached at their upper ends to the sides of the frame F.

It is thought that the construction, utility and advantages of this invention will now be quite apparent to those skilled in this art 85 without a more detailed description thereof.

The present embodiment of the invention has been disclosed in considerable detail merely for the purposes of exemplification 90 since in actual practice it attains the features of advantage enumerated as desirable in the statement of the invention and the above description.

It will be apparent that changes in the details of construction, and in the combination and arrangement of parts may be resorted to without departing from the spirit or scope of the invention as hereinafter claimed or sacrificing any of its advantages.

Having thus described my invention, what I claim as new is:

1. In combination with a tractor having a frame with a depending front bolster structure including steering operating mechanism, a bolster assembly comprising a pair of cross bars bolted to the front of the frame, a vertical plate secured to the centers of the cross bars and extending therebelow, a bolster bar secured to the plate and extending below the plate, an axle having its center bolted to the lower extremity of the bolster bar, steering knuckles on the ends of the axle, wheels on the steering knuckles, arms extending from the steering knuckles, a connecting rod between the arms, an arm operatively connected with the steering mechanism and pivotally connected with the center of the connecting rod.
2. In combination with a tractor having a frame with a depending front bolster structure including steering operating mechanism, a bolster assembly comprising a pair of cross bars bolted to the front of the frame, a vertical plate secured to the centers of the cross bars and extending therebelow, a bolster bar secured to the plate and extending below the plate, an axle having its center bolted to the lower extremity of the bolster bar, steering knuckles on the ends of the axle, wheels on the steering knuckles, arms extending from the steering knuckles, a connecting rod between the arms, an arm operatively connected with the steering mechanism and pivotally connected with the center of the connecting rod, said plate having a side flange along one side edge of the bolster bar.
3. In combination with a tractor having a frame with a depending front bolster structure including steering operating mechanism, a bolster assembly comprising a pair of cross bars bolted to the front of the frame, a vertical plate secured to the centers of the cross bars and extending therebelow, a bolster bar secured to the plate and extending below the plate, an axle having its center bolted to the lower extremity of the bolster bar, steering knuckles on the ends of the axle, wheels on the steering knuckles, arms extending from the steering knuckles, a connecting rod between the arms, an arm operatively connected with the steering mechanism and pivotally connected with the center of the connecting rod, a V-shaped brace having its ends fixed to the ends of the axle and extending rearwardly, a second V-shaped brace having its ends fixed to the frame and inclining downwardly and rearwardly, means pivotally connecting the apexes of the V-shaped brace.

60 In testimony whereof I affix my signature.
MICHAEL AUGUST ROGGE MAN.
